(57) **CLAIM**

The ornamental design for the shoe, as shown and described.

DESCRIPTION

FIG. 1 is a rear perspective view from one side of the shoe showing our new design;

FIG. 2 is a rear perspective view thereof from the opposite side;

FIG. 3 is a side view thereof;

FIG. 4 is a side view thereof from the opposite side;

FIG. 5 is a top plan view thereof;

FIG. 6 is a bottom plan view thereof;

FIG. 7 is a rear view thereof;

FIG. 8 is a front view thereof;

FIG. 9 is an enlarged fragmentary rear perspective view thereof, from one side; and,

FIG. 10 is an enlarged fragmentary a rear perspective view thereof, from the opposite side.

The broken line portions in the drawings are shown for illustrative purposes only and form no part of the claimed design.
